UNITED STATES PATENT OFFICE.

GUSTAV A. HUBEN, OF CHICAGO, ILLINOIS, ASSIGNOR OF ONE-HALF TO GORDON W. POST, OF CHICAGO, ILLINOIS.

RUBBER HEEL.

1,261,392

Specification of Letters Patent. Patented Apr. 2, 1918.

Application filed December 28, 1917. Serial No. 209,259.

To all whom it may concern:

Be it known that I, GUSTAV A. HUBEN, a citizen of the United States of America, and a resident of Chicago, in the county of 5 Cook, State of Illinois, have invented certain new and useful Improvements in Rubber Heels, of which the following is a specification.

This invention relates to elastic shoe heels 10 formed of india rubber or like resilient and wear resisting material, and has for its object:—

To provide an efficient correlated structural formation of the tread and attaching 15 surfaces of an elastic heel, adapted to afford increased elasticity to the heel in actual use, and by which a substantial attachment of the heel in place is attained by the ordinary fastening nails, all as will hereinafter more 20 fully appear.

In the accompanying drawing:

Figure 1, is a plan view of the upper or attaching face of a rubber heel constructed in accordance with the present invention.

25 Fig. 2, is a transverse section on line $\alpha-\alpha$, Fig. 1.

Fig. 3, is a plan view of the under or tread face of said rubber heel, with the correlated upper face shown in dotted lines.

30 Like reference numerals indicate like parts in the several views.

Referring to the drawing, 1 designates the body portion of the heel of any usual configuration and having the upper or attaching 35 surface, and lower or tread surface, which in the present improvement have the detail formations now to be described.

- 2 designates a raised marginal and continuous rib adapted to form and inclose a 40 shallow recess in the upper or attaching surface of the heel and provide a close marginal fit after the heel is applied to a shoe to retain a body of confined air and afford additional elasticity as usual in some of the 45 rubber heels in general use.

3 designates a central main projection arranged within the recess formed by the aforesaid marginal rim 2, and 4 designates a series of smaller projections surrounding 50 the main projection 3 and within the shallow recess aforesaid. The projections 3 and 4 are of a circular configuration and have a less height than the marginal rim 2, so that when the heel is nailed in place the body 55 portion of the heel will be slightly distorted

in an upward direction to insure a tight fit of the marginal rim 2 aforesaid.

5 and 6 designate continuous outer and inner depending ribs arranged in spaced relation, with the inner rib 6 adapted to form 60 and inclose a shallow recess in the under or tread surface of the heel, and which recess is subdivided by a series of ribs 7 radiating from a centrally disposed annular rib 8, with the entire series of said ribs on a common plane as shown. With the described construction an elastic and very effective non-slip tread surface is provided, and in the preferred construction shown in Fig. 3, the inner rib 6 aforesaid is of an indented 70 form.

8 designates the usual nail holes formed in the body portion 1 of the heel, and which in the present structure extends through adjacent projections 4 and open into the recess in the tread surface of the heel between the inner and outer ribs 5 and 6 aforesaid. With arrangement just described, the series of projections 4 are very effectively held in place after the application of the heel to a 80 shoe, and the resiliency of said projection utilized in an efficient manner.

Having thus fully described my said invention what I claim as new and desire to secure by Letters Patent, is:—

1. An elastic heel comprising a body portion having its attaching surface formed with a continuous marginal rib and a series of circular projections in the recess inclosed by said rib, and having its tread surface 90 formed with a pair of continuous marginal ribs in spaced relation, said body portion having nail holes passing through adjacent circular projections aforesaid and opening into the space between the marginal ribs of 95 the tread surface, substantially as set forth.

2. An elastic heel comprising a body portion having its attaching surface formed with a continuous marginal rib and a series of circular projections in the recess inclosed by said rib, the face of said projection being on a plane below the plane of the marginal rib, said body portion having its tread surface formed with a pair of continuous marginal ribs in spaced relation, and having nail 100 holes passing through adjacent circular projections aforesaid and opening into the space between the marginal ribs of the tread surface, substantially as set forth.

3. An elastic heel comprising a body por- 110

tion having its attaching surface formed with a continuous marginal rib and a series of circular projections in the recess inclosed by said rib, and having its tread surface formed with a pair of continuous marginal ribs in spaced relation, a central annular rib and a series of radiating ribs intermediate said annular rib and the inner mar-

ginal rib, said body portion having nail holes passing through adjacent circular projections aforesaid and opening into the space between the marginal ribs of the tread surface, substantially as set forth. ¹⁰

Signed at Chicago, Illinois, this 15th day of December, 1917.

GUSTAV A. HUBEN.
